VOLTAGE REGULATING DEVICE

Alfred C. Turtle, Montreal, Quebec, Canada

Application November 23, 1932, Serial No. 644,050

14 Claims. (Cl. 175—364)

This invention relates to lamp circuit potential regulating means for car lighting systems. It comprises a specially wound transformer having its secondary winding connected to the terminals 5 of a lamp circuit and its primary winding divided into at least two coils connected in parallel to a source of direct current through a special circuit making and breaking mechanism which functions, in response to a change in potential at the terminals of the direct current source, to effect a compensating change in the timing of the current impulses in one coil with respect to those in the other coil so that the output voltage of the transformer is thereby 10 maintained at an approximately constant value. In its preferred embodiment the circuit making and breaking mechanism comprises an interrupter in series with each primary coil, each interrupter embodying stationary and rotary 15 contacts, the latter being driven by a suitable D. C. motor connected to the direct current source so that the speed of the motor varies in response to potential changes occurring at the terminals of said source, and means including 20 a governor for automatically varying the angular displacement of the rotary element of one interrupter with respect to the corresponding rotary element of the companion interrupter in response to changes in the speed of the motor. 25 One particular advantage of this improved regulating means is that it eliminates the excessive resistance losses introduced in the lighting system by the regulators heretofore employed for the same purpose. Another advantage is that it 30 maintains the potential of the lighting circuit when the potential at the primary source is abnormally low, whereas the regulators heretofore used are effective only when the potential at the primary source rises above its normal 35 value.

Proceeding now to a more detailed description of the invention, reference will be had to the accompanying drawings, wherein—

Fig. 1 is a top plan view of a motor driven 45 interrupter assembly adapted to be used in accordance with this invention for automatically varying the phase relation of the primary coils of the transformer.

Fig. 2 is a side elevation of the assembly appearing in Fig. 1.

Fig. 3 is an end elevation of said assembly.

Fig. 4 is a transverse sectional view showing the relative arrangement and mounting of the stationary and rotary contacts of the adjustable 55 interrupter, said view being taken substantially

along the line 4—4 of Fig. 2 and certain parts that would otherwise appear being omitted for the sake of clearness.

Fig. 5 is a view in longitudinal section of the rotary elements of the interrupter appearing in Fig. 4.

Fig. 6 is a view in elevation of a fitting employed for connecting the rotary elements of the adjustable interrupter to a governor which determines the angular displacement of said elements.

Fig. 7 is a view in longitudinal section of the rotary element of the remaining or non-adjustable interrupter.

Fig. 8 is a transverse sectional view along the line 8—8 of Fig. 7.

Fig. 9 is a detail perspective view illustrating the construction and mounting of a special switch employed in accordance with this invention.

Fig. 10 is a wiring diagram of a lighting system embodying said invention.

Fig. 11 is a perspective view of a brush and brush housing assembly provided in accordance with this invention.

Fig. 12 is a sectional view taken along the line 12—12 of Fig. 2.

Fig. 13 is a bottom plan view of a modified interrupter assembly equipped with a spark quenching device.

Fig. 14 is a side elevation of the assembly appearing in Fig. 13.

Referring more particularly to the drawings, 11 designates a shaft mounted in suitable bearing brackets 12 carried by a base 13. This shaft 35 carries the rotary contact elements of the interrupters generally indicated at A and B and is driven by a suitable shunt wound direct current motor 14 of the over-saturated field type, whose operating speed varies according to variations in the potential of the energizing current supplied thereto.

The rotary contact assembly of the interrupter A is shown in detail in Fig. 5. It comprises a sleeve 15 having an axial bore 16 through which the shaft 11 extends. Said sleeve is fitted with a pin 17 which works in the spiral shaft slot 18 (see Fig. 1) so that as the sleeve is moved along the length of the shaft it is also turned to vary the angular displacement of the diametrically opposed contacts 19, carried at the outer surface of the sleeve, with respect to the angular displacement of the corresponding contacts 65 of interrupter B. These contacts 19 comprise segments of conducting material fitted (see Fig. 4) 55

between segments 20 of insulating material, said segments being clamped to the outer surface of the sleeve between a shoulder 21 and a clamping nut 22, the inner faces of the shoulder and clamping nut being inclined as at 23 to overlie the mitred ends 24 of the segments whereby the latter are securely held against radial displacement during high speed rotation of the sleeve 15. One end of the sleeve 15 projects beyond the nut 22 and carries a disc 25 in threaded engagement therewith. The other end of the sleeve projects beyond the shoulder 21 and is rotatably connected to the axially movable end member 26 of the governor generally indicated at 27 in Fig. 1. 10 As shown to advantage in Figs. 5 and 6, said member 26 comprises two halves designated 26a and 26b which embrace the end of the sleeve 15 projecting beyond the shoulder 21 and are fastened together by bolts 28 which engage in an 20 outwardly facing annular groove 29 formed in the sleeve so that the latter is held against axial movement relative to the member 26 but is capable of independent rotary movement.

The two halves of the axially movable governor 25 member 26 are connected by lugs 30 and pivots 31 to corresponding ends of a pair of links 32. The remaining ends of the links 32 are connected by pivots 33 to similar links 34 which, in turn, are connected by lugs 35 and pivots 36 to the remaining end member 37 of the governor, said member 37 being adjustably fixed to the shaft 11 by the clamping nuts 38 so that the position of this member may be adjusted to regulate the tension of the governor spring 39. From 30 this description it will be apparent that variations in the speed of the motor 14 and the shaft 11 in response to changes in the potential of the current supplied to the motor results in the sleeve 15 being moved axially of the shaft in one direction or the other, in the course of which the sleeve is turned about the shaft by means of the pin 17 and the groove 18 to change the angular displacement of the contacts 19.

During rotation of the shaft 11 the rotary contacts 19 engage successively with four stationary contact brushes 41, 41a, 41b and 41c made of carbon or other suitable conductive material. Each brush is slidably mounted in a suitable housing 42 and is pressed inwardly by a spring 43. The several housings 42 are carried between a pair of supporting plates 44 made of any suitable insulating material, said plates having extensions 45 which, together with an interposed spacer 46, are fastened as at 47 to an upright 48 carried by upper and lower rods 49 mounted in the bearing brackets 12. The housings 42 may be of any suitable construction. As here shown, each housing comprises four metal walls (42a, 42b, 42c and 42d) defining a rectangular guideway 42e in which the brush works, said guideway being open at the inner end of the housing and being closed at the opposite end by a suitable cover plate 42f, the spring 43 being interposed between the cover plate 42f and the outer end of the brush 41. Each brush housing is equipped with a terminal 50 passing therethrough and through suitable apertures in the housing supporting plates 44.

An upright 52 similar to the upright 48 is 70 carried by the previously mentioned rods 49 and serves as a mounting for a switch generally indicated at 53 (see Figs. 1 and 9). The movable contact 54 of this switch is provided with bearings 55 rotatably mounted on the bight portion 56 of a U-shaped bolt. The arms 57 of

this bolt pass through suitable openings in the upright 52 and are clamped in place by means of the clamping shoulders 58 and the clamping nuts 59. The movable contact 54 is formed to present plate-like portions 54a and 54b. A 5 spring 60 arranged as shown in Fig. 9 tends to swing the plate portion 54a of contact 54 into engagement with a pair of stationary contact terminals 61 and 62 also carried by the upright 52. The plate portion 54b of contact 54 is 10 equipped with a terminal 54c and carries a projecting member 54d made of insulating material. When the various parts are positioned as shown in Fig. 1 the disc 25 engages the insulating member 54d carried by the movable switch contact 15 54 and serves to hold the plate portion 54a of this contact out of engagement with the stationary contact terminals 61 and 62. A particular purpose of this switch will be explained herein-after. 20

The movable contact assembly of interrupter B is shown in Figs. 7, 8 and 12. It comprises a metal sleeve 64 carrying at its outer surface a pair of diametrically opposed conducting segments 65 fitted between alternating segments 66 of insulating material, said segments being clamped in place between the shoulder 67 and the clamping nut 68, the ends of the segments being mitred as at 69 to fit the inclined inner edges 70 of the shoulders 67 and the nut 68. 30 Sleeve 64 is fixed to rotate with the shaft 11 by means of the set screw 71. The rotary contacts 65 of interrupter B co-operate with four brushes 72, 72a, 72b and 72c which are mounted in exactly the same manner as brushes 41, 41a, 35 41b and 41c except that in the case of interrupter B the extensions 45 of the insulating plates 44 between which the brush housings are mounted are fastened to the upright 52.

In describing the operation of the foregoing 40 construction reference will be had to the wiring diagram appearing in Fig. 10. In this figure 80 designates a single core transformer having its secondary winding 81 connected to the terminals 82 of a lamp circuit 83. The primary of the 45 transformer is divided into two coils 84 and 85 each having one terminal connected by conductor 86 and switch 87 to the negative terminal 88 of a direct current source such as a storage battery 89. The remaining end of coil 84 is connected by conductors 90 to the brushes 41 and 41a of interrupter A. The remaining brushes 41b and 41c of this interrupter are connected by conductors 91 and 92 with the stationary contact 61 of the automatic switch 53. 50

The remaining end of coil 85 is connected by conductors 93 to the brushes 72 and 72a of interrupter B. The two remaining brushes 72b and 72c of interrupter B are connected by conductors 94 and 92 to the aforesaid stationary 60 contact 61 of the switch 53.

The positive terminal 88a of the battery 89 is connected through switch 87 and conductors 95 and 96 to the terminals 54c carried by the movable contact 54 of the switch 53. Conductor 65 95 also connects the positive terminal of the battery to one terminal of the armature starting resistance 97 and the shunt field 97a of the motor. The remaining terminal of the starting resistance 96 is connected to the positive terminal 98 of the motor 14 by a conductor 99 which is also connected by a branch conductor 100 to the stationary terminal 62 of the automatic switch 53. The negative terminals 91 of the motor 14 and the negative terminal of the 70 75

shunt field 97a are connected through conductors 102 and 86 and switch 87 to the negative side of the battery 89. When the motor 14 is at rest the movable contact 54 of switch 53 is held in open position by engagement with the disc 25 as shown to advantage in Fig. 1. With the parts in this position closure of switch 87 causes current to flow from the positive to the negative side of the battery via the conductor 95, the motor starting resistance 97, the motor terminals 98 and 101, the shunt field 97a and the conductors 102 and 86. As the motor attains its normal operating speed the governor 27 acts to move the sleeve 15 and the disc 25 to the left until the movable contact 54 of the switch 53 is free to move into engagement with the stationary contacts 61 and 62 under the influence of the spring 60 thereby closing the automatic switch 53. This closure of switch 53 serves to cut out the motor starting resistance 97 and to cut in the interrupters A and B and the primary coils 84 and 85. With the switch 53 in closed position the flow of current from the positive side of the battery to the motor terminal 98 is via the conductors 95 and 96, switch contacts 54 and 62 and conductors 100 and 99 thus bypassing the starting resistance 97 included in the original circuit. Current also flows in the closed position of switch 53 via conductors 95 and 96, switch contacts 54, 62 and 61 and conductors 91, 92 and 94 to the brushes 41b and 41c of interrupter A and the brushes 12b and 12c of interrupter B, and thence via the co-operating rotary contacts of the interrupters 35 and the coils 84 and 85 to the negative side of the battery.

The sliding and rotary movement imparted to the sleeve 15 of the interrupter A by the governor 27 as the motor 14 attains its normal operating speed fixes the normal angular displacement of the rotary contacts 19 with respect to the rotary contacts 65. If there is any change of potential at the battery terminals this immediately produces a change in the operating speed of the motor 14. The governor 27 thereupon acts to effect a certain further angular displacement of the sleeve 15 and contacts 19 of interrupter A which results in a change in the timing of the impulses produced in coil 84 with respect to those produced in coil 85 that compensates for the change in the potential of the current supplied to said coils and maintains the output potential of the secondary 81 at an approximately constant value. In other words, the changes which are made in the angular displacement of the contacts 19 of interrupter A in response to potential variations at the battery terminals serves to advance or retard the interruptions of the primary circuit including the coil 84 with respect to the interruptions of the parallel primary circuit including the coil 85 so that the effective flux producing ampere turns of the two primary coils remains approximately constant. In this connection it will be understood that the increased or decreased frequency of the interruptions due to changes in the operating speed of the motor 14 are compensated for by an accompanying shortening or lengthening of the duration of the contact periods of the interrupters so that the average voltage in the secondary of the transformer will be maintained approximately constant irrespective of changes in the speed of the operating motor due to changes of potential current at the terminals of the direct current source.

In order to prevent arcing at the interrupter contacts, condensers 105 and 106 may be provided as indicated in Fig. 10. As here shown, condenser 105 is connected across the brushes 41 and 41b of the interrupter A while the remaining condenser 106 is connected across the brushes 12 and 12b of the interrupter B. Reference characters 107 and 108, in Fig. 10, designate a pair of rectifying units shunted across the leads to the primary windings of the 10 transformer to prevent arcing at the interrupter contacts due to the inductive effect of the primary coils. These rectifying units have their output terminals connected to the leads 90 and 93 and their input terminals connected to the lead 15 86 and are constructed in a well known manner so that, when thus connected, they will offer a high resistance to the flow of current therethrough from the leads 90 and 93 while offering relatively low resistance to the flow of current 20 therethrough in the opposite direction from the primary coils when the latter, due to their inductive effect and to the opening of the primary circuit at the interrupters, are acting as sources of energy that would tend to produce arcing 25 at the interrupter contacts in the absence of the valve action or short circuiting effect of the rectifiers. A choke coil may be used in connection with the rectifying units as indicated at 109 in order to prevent a too rapid decrease in 30 transformer current.

In Figs. 13 and 14 I have shown a slight modification illustrating the manner in which each interrupter may be equipped with a spark quenching device for reducing arcing at the 35 main interrupter contacts. The interrupter shown in these figures comprises two brushes 111 and 111a co-operating with the rotary contacts which are the same as described in connection with the previous figures. In this case, however, the metal sleeve C which carries the rotary interrupter contacts D has one end extended beyond the adjacent brush support 44 and equipped with a metal cam 112 which is electrically connected to the sleeve and serves as 40 a supplementary rotary contact element. This cam 112 has two cam lifts designated 113 and 114. The cam lift 113 co-operates with a series of metal washers 115 carried by a lever arm 116. One end of lever arm 116 is pivoted, as at 50 117, and is electrically connected to the brush 111, as indicated at 118. The other end of the lever arm 116 is apertured for the passage of a screw 119 and is confined between the screw carried springs 120 and 121, the tension of 55 which may be regulated by the adjusting nuts 122 and 123. The remaining lift 114 of cam 112 co-operates with a series of washers 124 carried by a lever 125. This lever 125 has its pivoted end 126 electrically connected to the brush 111a 60 as indicated at 127 and its opposite end confined between the springs 128 and 129 carried by a screw member 130 corresponding to the previously mentioned screw member 119.

From the foregoing description it will be understood that the washers 115 and 124 constitute supplementary contacts in parallel with the brushes 111 and 111a which are periodically bridged by the cam 112 whose cam lifts 113 and 114 are arranged so that the angular displacement 70 of their points 113a and 114a is different from that of the main rotary interrupter contacts D. Due to this arrangement it will be seen that when the main interrupter contacts D pass out of engagement with the brushes 111 and 111a 75

practically no arcing occurs since the primary circuit, including the brushes 111 and 111a, is still maintained by reason of the fact that the washers 115 and 124 which are in parallel with these brushes are connected together by the cam 112. As viewed in Fig. 14 the cam rotates in a clockwise direction and the primary circuit is broken when the points 113a and 114a of the cam pass out of engagement with the washers 115 and 124. The springs associated with the free ends of the lever arms 116 and 125 serve to yieldingly maintain the washers 115 and 124 in a position to co-operate with the cam lifts as herein described.

15 Having thus described my invention, what I claim is:

1. The combination of a transformer having two primary coils connected, in parallel, to a source of direct current and means for changing the timing of the impulses produced in one coil with respect to those produced in the other coil to compensate for changes in the potential of the current supplied thereto.

2. The combination of a transformer having two primary coils connected, in parallel, to a source of direct current and means acting in response to potential changes at the terminals of said source for effecting a compensating change in the timing of the impulses produced in one coil with respect to those produced in the other coil so that the output voltage of the transformer is maintained approximately constant.

3. The combination of a transformer having two primary coils connected, in parallel, to a source of direct current, an interrupter in series with each coil, and means for varying the relative timing of said interrupters in response to changes in the potential supplied to said coils.

4. The combination of a transformer having two primary windings and a secondary winding on a common core, a source of direct current to which the primary windings are connected in parallel, an interrupter in series with each primary winding, and means, responsive to potential variations at said source, for changing the relative timing of the interrupters so that the output potential of the transformer is maintained approximately constant.

5. The combination of a transformer having two primary windings and a secondary winding on a common core, a source of direct current to which the primary windings are connected in parallel, an interrupter in series with each primary winding, a motor for operating said interrupters connected in circuit with said source so that the speed of the motor is determined by the potential at said source and varies therewith and a governor functioning to automatically vary the timing of one of said interrupters with respect to the timing of the companion interrupter when the speed of the motor varies in response to potential variations at said source.

6. Means for supplying a lamp circuit with alternating current of approximately constant potential from a primary source of variable potential comprising a transformer having a secondary winding and two primary windings on a common core, the secondary winding being included in said circuit, a source of direct current to which the primary windings are connected in parallel, an interrupter in series with each coil and means for varying the relative timing of said interrupters in response to potential variations at said source.

75 7. The combination with a source of direct

current of a transformer having two primary windings connected in parallel to said source and means for producing impulses in said coils including means for variably timing the impulses produced in one coil with respect to those produced in the other coil to regulate the output voltage of the transformer.

8. The combination with a source of direct current of a transformer having two primary windings connected in parallel to said source, an interrupter in series with each coil and means for varying the timing of one interrupter with respect to the timing of the other interrupter to control the output voltage of the transformer.

9. The combination of a transformer having two primary coils connected in parallel to a source of direct current, an interrupter in series with each coil, means for varying the relative timing of said interrupters in response to changes in potential at the terminals of said source, and means connected across the terminals of each coil to prevent arcing at the interrupter contacts due to the inductive effect of the coils when the primary circuits are broken at the interrupters.

25 10. The combination of a transformer having two primary coils connected in parallel to a source of direct current, an interrupter in series with each coil, a condenser connected in circuit with each interrupter to reduce arcing at the interrupter contacts and means for varying the relative timing of said interrupter in response to changes in potential current at the terminals of said source.

30 11. The combination with a source of direct current of a transformer having two primary windings connected in parallel to said source, an interrupter in series with each primary winding, a motor for operating said interrupters connected in circuit with said source so that the speed of the motor is determined by the potential at the terminals of said source, a governor functioning to automatically vary the timing of one interrupter with respect to the other interrupter when the speed of the motor varies in response to potential variations at said source, and a switch mechanism functioning automatically to disconnect the interrupters when the motor is at rest and to connect the interrupters in series with their respective primary windings when the motor has attained a predetermined operating speed.

35 12. The combination with a source of direct current and a load circuit of a transformer having two primary windings connected in parallel to said source and a secondary winding connected to said load circuit, an interrupter in series with each primary winding, a direct current motor for operating said interrupters energized from said direct current source so that the speed of the motor varies in response to potential variation at said source, a governor functioning to automatically change the timing of one interrupter with respect to the remaining interrupter when the speed of the motor varies, a switch arranged to automatically assume an open position when the motor is at rest so as to open circuit the interrupters and the primary windings connected in series therewith, a starting resistance including in the motor circuit, means for automatically closing said switch to include the interrupters and primary windings in circuit with said source and means including said switch for bypassing said starting resistance when the switch is in its closed position.

13. The combination with a transformer and a source of direct current included in the primary circuit of the transformer of interrupter means functioning, in response to changes in the potential at said source, for effecting a compensating change in the interruptions of said circuit so that the output voltage of the transformer is thereby maintained at an approximately constant value.
- 5 14. In a system of electrical distribution the combination of a direct current source, a load circuit, means including an adjustable inter-
rupter for connecting said circuit to said source whereby an alternating current is produced in said circuit, a direct current motor connected to said source to operate at a speed proportionate to the voltage across the terminals of said source and means actuated by said motor for adjusting the interrupter to maintain the voltage of the load circuit at a substantially constant value throughout a wide range of voltage variations at the terminals of said source.
- 10

ALFRED C. TURTLE.
